UNITED STATES PATENT OFFICE

172,825

POPCORN MACHINE

Charles J. Cretors, Highland Park, Ill., assignor to
C. Cretors & Co., Chicago, Ill., a corporation of Illinois

Application June 24, 1953, Serial No. 25,635

Term of patent 14 years

(Cl. D81—10)

To all whom it may concern:

Be it known that I, Charles J. Cretors, a citizen of the United States and a resident of Highland Park, county of Lake, and State of Illinois, have invented a new, original, and ornamental Design for a Popcorn Machine, of which the following is a specification, reference being had to the accompanying drawing forming a part thereof, in which:

Fig. 1 is a front perspective view of a popcorn machine showing my new design, and Fig. 2 is a rear perspective view thereof.

I claim:
The ornamental design for a popcorn machine, as shown.
